UNITED STATES PATENT OFFICE.

ALFRED WILLIAMS AND LEO DAFT WILLIAMS, OF LONDON, ENGLAND.

THERMOTELPHONIC RECEIVER.

Application filed April 24, 1920. Serial No. 376,389.

To all whom it may concern:

Be it known that we, ALFRED WILLIAMS and LEO DAFT WILLIAMS, both citizens of the United States of America, residing at 5 London, England, have invented new and useful Improvements in Thermotelephonic Receivers, of which the following is a specification.

This invention relates to improvements in 10 telephone receivers of the type described in our application Ser. No. 142009 filed Jan. 12, 1917.

We have found by experiment that the efficiency of receivers of the type mentioned 15 is considerably improved by arranging the metal foil or leaf in such a manner that the segments or strips of foil or leaf are disposed face to face and as nearly as practicable parallel to each other and also as near 20 together as is compatible with safety from short-circuiting and with the possibility of obtaining good cooling by convection. By "face to face" we mean an arrangement in which the strips or segments of foil or leaf 25 face each other as do the two halves of an uncrossed belt connecting two pulleys.

To more fully explain the essential features of the invention, reference is made to the accompanying drawings in which

30 Fig. 1 is an elevation of a simple embodiment of the invention;

Fig. 2 is a plan view thereof; and

Figs. 3-7 inclusive are plan views of modified forms of the invention.

35 In Figs. 1 and 2 P denotes metal pegs secured in a base A of vulcanite or other suitable insulating material. On these pegs are supported strips S of metal foil of the character described in our application above referred to. While there is considerable 40 latitude in regard to the length, width and spacing of the strips S, we have found that a width B of $\frac{1}{8}$ ", a length of $\frac{3}{8}$ " and a distance C of $\frac{3}{2}$ " bring about very good results.

45 Fig. 3 shows a strip T of foil arranged in the form of a spiral having its convolutions disposed in the same general plane and supported on a relatively large number of pegs P₁. The distance C₁ between the convolutions is preferably the same or approximately the same as the distance C in Figs. 1 and 2.

50 In Fig. 4 a strip V forms a plurality of triangular convolutions in the same general plane as in Fig. 3. Pegs P₂ are correspond-

ingly placed to support the strip. The distance C₂ between the convolutions is again substantially the same as C in Figs. 1 and 2.

Fig. 5 shows a zig-zag form of strip W supported on pegs P₃ at the vertices. The length L₁ is preferably the same as L in Figs. 1 and 2 and the distance C₃ between adjacent vertices is also preferably the same as C, Figs. 1 and 2.

Fig. 6 shows a modified form of zig-zag arrangement in which the different sections X run parallel courses and are supported by correspondingly placed pegs P₄ in close proximity to each other, the distance C₄ corresponding again to C in Figs. 1 and 2.

Fig. 7 shows an arrangement differing from the arrangements previously described but having in common with them the characteristic feature that sections Z of the foil run face to face and are supported by pegs P₅ parallel to each other at a distance C₅ of the order of C in Figs. 1 and 2.

Within the broader aspect of the invention it is possible to provide other forms or combinations of forms defining the characteristic features above pointed out.

While we cannot, of course, precisely and positively explain the reasons why arrangements having the above mentioned characteristics show a greater efficiency than other forms, it is our opinion that due to the face to face relation of the strips or sections the amount of heat radiation is reduced although sufficient provision is made for effective cooling. Whether this explanation is correct must be left to future investigation. The fact remains, however, that all forms of devices above referred to show a marked improvement over other forms not having the characteristics pointed out.

We claim:

1. In a telephone receiver of the type described, a bridge of metal foil composed of a plurality of sections which are disposed between two adjacent parallel planes, substantially at right angles thereto, some of the sections being disposed face to face in substantially parallel relation to each other.

2. In a telephone receiver of the type described, a bridge of metal foil, composed of a plurality of sections which are disposed between two adjacent parallel planes, substantially at right angles thereto, some of the sections being disposed face to face in substantially parallel relation and in close proximity to each other.

3. In a telephone receiver of the type described, a bridge of metal foil, composed of a relatively large number of sections which are disposed between two adjacent parallel planes substantially at right angle thereto, the sections being formed in groups the members of which are substantially parallel and in close proximity to each other.
4. In a telephone receiver of the type described, a bridge of metal foil, composed of a plurality of sections disposed between two adjacent parallel planes substantially at right angle thereto and in close proximity to one another, the sections being arranged in groups the members of which are parallel to one another.
5. In a telephone receiver of the type described, a bridge of metal foil, composed of a relatively large number of angularly related sections normal to and intersected by the same plane of reference, the sections being formed in groups the members of which

are substantially parallel and in close proximity to each other.

6. In a telephone receiver of the type described, a base of insulating material, a bridge of metal foil composed of a plurality of sections disposed substantially normal to the base and pegs secured in the base for supporting the bridge, some of the sections being disposed face to face and in substantially parallel relation to each other.

7. In a telephone receiver of the type described, a bridge of metal foil having a plurality of convolutions disposed in the same general plane and in close proximity to each other, a base of insulating material and pegs secured in the base for supporting the bridge in parallelism with the surface of the base.

In testimony whereof we have signed our names to this specification.

ALFRED WILLIAMS.
LEO DAFT WILLIAMS.
